DESIGN FOR A COMBINED GRAVE PRESERVER AND MARKER

Robert W. Wahl, Broken Bow, Nebr.

Application August 5, 1938, Serial No. 79,136

Term of patent 14 years

To all whom it may concern:

Be it known that I, Robert W. Wahl, a citizen of the United States of America, residing at Broken Bow, county of Custer, and State of Nebraska, have invented a new, original, and ornamental Design for a Combined Grave Preserver and Marker, of which the following is a specification, reference being had to the accompanying drawing forming a part thereof, wherein:

I claim:

The ornamental design for a combined grave preserver and marker, as shown.

ROBERT W. WAHL.
